SERVING DEVICE FOR CARD TABLES

Filed Nov. 30, 1929

By *Watson E. Coleman*
Attorney

UNITED STATES PATENT OFFICE

JOHN R. GOLSON, OF BENNETTSVILLE, SOUTH CAROLINA

SERVING DEVICE FOR CARD TABLES

Application filed November 30, 1929. Serial No. 410,794.

This invention relates to card tables and particularly to means for supporting plates, ash trays, tumblers and the like in conjunction with the card table.

5 The general object of the invention is to provide utensil supports pivotally mounted upon the under face of the card table and movable outward to an exposed position whenever it is desired to support a utensil, 10 thus doing away with the placing of ash trays, drinking glasses, plates, etc., on the top of the table, thus keeping the top of the table clean and preventing it becoming marred and marked.

15 A further object is to provide a device of this character so constructed that it will not interfere with the action of folding or unfolding the legs of the table and another 20 object is to provide means for holding the plate supporting bracket, as it may be termed, either in position beneath the table or in an exposed position and prevent it from turning over under weight.

Other objects will appear in the course of 25 the following description.

My invention is illustrated in the accompanying drawings, wherein:—

Figure 1 is an under side plan view of a card table having my server applied thereto; 30 Figure 2 is a fragmentary sectional view of an enlarged section through the card table and showing the server extended;

Figure 3 is a fragmentary side elevation of a portion of the card table showing the 35 clip for holding the server, the arm of the server being in section.

Referring to these drawings, A designates a folding card table of the character ordinarily used today. This table has legs B. 40 These legs B are hinged as usual so that they may be turned inward against the table top and extend, under these circumstances, parallel to the side edges of the table. This table is also provided with the lateral rails C and such tables are usually provided with the intermediate rail D which braces the table top.

My invention consists in applying to this 45 table top, a swingable bracket carrying what may be termed a tray. The bracket is des-

ignated 10. The bracket is angular in form and preferably formed of strap iron or other metal, the bracket adjacent its inner end being twisted at 12 so as to provide a portion 13 disposed in a plane offset with relation to the plane of the bracket 10. This portion 13 extends at an angle to the portion 10 and extends into a slot or other member formed in the corresponding rail C, it being pivoted thereto as at 14. The table leg B 55 when it is turned inward against the top extends over this portion 13, which abuts flat against the inner face of the table top.

The angularly disposed portion or arm 13 is relatively short, while the outer portion 60 10 is relatively long and at its end is bifurcated as at 15.

Mounted upon the arm 10 adjacent its bifurcated portion 15 is a disk or tray 16 65 preferably having a slightly flanged or up-turned rim like an ordinary tray. This is attached to the arm by any suitable means, as for instance, by a rivet 17.

It will be seen that when this bracket or arm is extended outward, it extends beneath 70 a rail C and unless it is supported in some way, the weight of an object would tend to force the arm or bracket downward. To this end I mount upon the rail C for each bracket, if more than one bracket is used, a metal clip 75 18 of strap iron, one end of which is bent upon itself so as to form a double thickness and through this bent portion the bolt 19 passes. This clip, therefore, receives between it and the rail C the arm or bracket 10 when 80 this bracket is extended, thus supporting the arm against any downward movement and causing the tray to be rigidly held in position, the bifurcated portion 15 of the bracket 85 10 acting, of course, to prevent any lateral 90 tilting movement of the tray. The tray is preferably of metal. In order to support the bracket when it is turned inward, I provide a second clip 20 constructed in exactly the same manner as the clip 18 but longer and 95 mounted upon the brace D within which the edge of the tray may be engaged when the bracket is turned inward to carry the tray fully beneath the table top.

It will be understood that four of these 100

brackets are preferably used so that when the brackets are extended, there will be a bracket for each of the four sides of the table, thus providing for four players using 5 the four trays or servers.

It will be noted that while this construction provides a plurality of serving trays which are normally disposed entirely beneath the table, and any one of which may be extended beyond the table, yet the trays when disposed entirely beneath the table top, do not in any way interfere with the folding inward of the legs B.

I do not wish to be limited to the particular form of table shown as these serving trays might be mounted upon tables of different character and yet achieve the same result.

I claim:

20. 1. The combination with a table having side rails, of a bracket having one end pivoted to the margin of the table, the outer portion of the bracket being deflected away from the table top and carrying a serving tray,

25. the bracket being swingable from a position with the serving tray entirely beneath the table top to a position where the serving tray is projected beyond the table top, a clip mounted upon another rail of the table and

30. with which the bracket is engageable when the bracket is swung outward, this clip acting to support the bracket against downward pressure, and a clip mounted upon the table beneath the table top engageable with the

35. tray to hold the bracket and tray against downward movement when the tray is disposed beneath the table top.

2. The combination with a table having side rails, of a bracket having one end pivoted to the margin of the table, the outer portion of the bracket being deflected away from the table top and carrying a serving tray, the bracket being swingable from a position with the serving tray entirely beneath

45. the table top to a position where the serving tray is projected beyond the table top, a clip mounted upon another rail of the table and with which the bracket is engageable when the bracket is swung outward, this clip acting

50. to support the bracket against downward pressure, and a clip mounted upon the table beneath the table top engageable with the tray to hold the bracket and tray against downward movement when the tray is disposed beneath the table top, each clip being

55. formed of a strip of metal folded upon itself adjacent one end and having a bolt passing through the folded portion of the strip and engaging it with the rail.

60. 3. The combination with a table having folding legs, each pivotally engaged with the table top adjacent one corner of the table top, of a plurality of brackets, each angularly bent and having its inner end deflected and inserted between one of the rails and the table

top and pivoted thereto, the outer or free end of each bracket carrying a serving tray, means mounted upon the several rails of the table for engaging each bracket when it is projected and supporting the bracket against downward movement, a reinforcing rail extending across the table, and means mounted upon said reinforcing rail engaging the several trays and holding the trays and brackets from downward movement when the brackets are disposed with the trays beneath the table top.

In testimony whereof I hereunto affix my signature.

JOHN R. GOLSON.
